UNITED STATES PATENT OFFICE.

CHARLES J. KERN, OF BUFFALO, NEW YORK, ASSIGNOR TO INVENTORS PRODUCT COMPANY, INC., A CORPORATION OF NEW YORK.

TOWEL-HOLDER.

1,229,475.

Specification of Letters Patent. Patented June 12, 1917.

Application filed May 6, 1916. Serial No. 95,859.

To all whom it may concern:

Be it known that I, CHARLES J. KERN, a citizen of the United States of America, residing at 342 Ellicott Square, Buffalo, New 5 York, in the county of Erie and State of New York, have invented certain new and useful Improvements in Towel-Holders, of which the following is a specification.

This invention relates to towel dispensers.

10 One object is to provide a simple, strong and easily manufactured device designed to support a roll of toweling material in such a manner as to dispense towels of definite length.

15 Another object resides in the provision of a towel dispensing device having a roll support that may be used with any form of holder, and embodying means to rotatably support a roll of toweling material so that 20 towels of definite length may be dispensed and also embodying means whereby the roll of toweling material is prevented from slipping on the supporting means during operation of the same.

25 A still further object resides in the provision of a towel dispenser embodying means adapted to rotatably support the toweling material in such manner that towels of definite length may be dispensed under the 30 influence of a pull of the web of toweling material to thereby rotate the roll of toweling material and the supporting means therefor to a given degree in combination with means to automatically return the supported roll of toweling material to normal 35 position.

With the above and other objects in view, the present invention consists in the combination and arrangement of parts herein- 40 after more fully described, illustrated in the accompanying drawings, and particularly pointed out in the appended claim, it being understood that changes may be made in the form, proportion, size and minor details 45 without departing from the spirit or sacrificing any of the advantages of the invention.

In the drawings:—

Figure 1 is a front elevation with the roll of toweling material removed.

50 Fig. 2 is a top plan view with the roll of toweling material removed.

Fig. 3 is an end view with the roll of toweling material removed.

Fig. 4 is a transverse section through the

device with the roll of toweling material 55 mounted on the supporting plate.

Fig. 5 is a detail perspective of the supporting plates for the toweling material.

Referring now more particularly to the accompanying drawings, the character 1 indicates a shaft provided with suitable end bearings 2 and 3. These bearings permit the shaft to be readily introduced into and easily removed from the slots 4 at each end of the holder 5, in which slots the shaft is 60 held against rotation. Any suitable form of holder may be employed.

A pin 6 extends laterally from the said shaft, being located at a suitable point between the ends of the shaft. 70

A plate 7 is rotatably mounted on the shaft and preferably made of sheet metal and provided with slots 8 adjacent the ends of said plate. The metal of the plate 7 on the opposite sides of each slot 8 is bent in 75 opposite directions, as indicated at 9 and 10, to provide bearings to receive the shaft 1. At the center of the said plate is an elongated aperture 11 having a notch 12 80 therein.

A coiled spring 13 surrounds the shaft 1, one of its ends being attached to said shaft, as indicated at 14, its other end being attached to the plate 7, as indicated at 15. Suitable washers 16 are interposed between 85 the holder 5 and the plate 7 to prevent friction between the parts.

In practice, the roll of toweling material is mounted on the plate 7, against slipping thereon, and the plate lies normally in contact with the pin 6 on the shaft 1. A pull on the free end of the toweling material causes the roll of paper and the said plate to rotate together, the plate moving away from the pin 6 on the shaft 1 against the tension 90 of the spring 13, the notch 12 in the plate 7 permitting the plate to clear the pin 6 and continue to rotate until the opposite side of the plate contacts with the pin 6 on the shaft 1, resulting in substantially a complete 95 revolution of said plate. At this point the plate is at the limit of its rotary movement and a predetermined length of toweling 100 is unwound from the roll and may be disconnected from the web. Upon disconnection of the towel of predetermined length, the spring 13 will return the plate and the roll of paper to normal position, the notch 105

17 permitting the plate to clear the pin 6 on the shaft 1. The device is then in position for another operation as described above.

What I claim is:—

5 In a towel dispensing device, a holder, a shaft fixedly mounted in said holder, a stamped sheet metal plate rotatably mounted on said shaft and adapted to support a roll of toweling material, said plate having
10 a central aperture with a notch leading into said aperture, a pin on the shaft, one side of said plate being normally in contact with one side of said pin, means for rotating said plate, the said notch permitting the pin to
15 clear the said plate and permit the said plate to rotate until the opposite side of the plate

contacts with the other side of said pin, thereby permitting a single revolution of said plate and allowing a predetermined length of toweling to be unwound from said 20 roll, a spring having one end attached to said shaft and its other end attached to the said plate, whereby the plate is returned to its normal position upon the severing of the unwound material from the roll. 25

In testimony whereof I affix my signature in the presence of two witnesses.

CHARLES J. KERN.
